Primary Examiner — Angela J Lee*Assistant Examiner* — Shawn T Gingrich(74) *Attorney, Agent, or Firm* — Quarles & Brady LLP(57) **CLAIM**

The ornamental design for a connector, as shown and described.

DESCRIPTION

FIG. 1 is a perspective view of a front, top, and left side of an ornamental design for a connector;

FIG. 2 is a front elevational view of the of the connector of FIG. 1;

FIG. 3 is a rear elevational view of the connector of FIG. 1;

FIG. 4 is a right side elevational view of the connector of FIG. 1;

FIG. 5 is a left side elevational view of the connector of FIG. 1;

FIG. 6 is a top plan view of the connector of FIG. 1;

FIG. 7 is a bottom plan view of the connector of FIG. 1;

FIG. 8 is a perspective view of a rear, top, and left side of the connector of FIG. 1;

FIG. 9 is a perspective view of a front, top, and right side of the connector of FIG. 1; and,

FIG. 10 is a perspective view of a front, top, and right side of the connector of FIG. 1.

The dash-dash-dash lines are included for the purpose of illustrating portions of the connector that form no part of the claimed design. The dash-dot-dash line showing a boundary line forms no part of the claimed design.
